[57] CLAIM

The ornamental design of a fishing weigh scale, as
shown and described.

DESCRIPTION

FIG. 1 is a top, front and left side perspective view of a
fishing weigh scale showing my new design;

FIG. 2 is a left side elevational view;

FIG. 3 is a right side elevational view;

FIG. 4 is a front elevational view;

FIG. 5 is a rear elevational view;

FIG. 6 is a top plan view; and,

FIG. 7 is a bottom plan view thereof.

FIG. 1 has been drawn on a slightly reduced scale with
respect to FIGS. 2-7.

FIG.1

FIG. 2

FIG. 3

FIG. 4

FIG. 5

FIG. 6
